CLAIM

The ornamental design for a light fixture hex shroud, as shown.

DESCRIPTION

FIG. 1 is a perspective view of the light fixture hex shroud; FIG. 2 is a reverse angle perspective view of the light fixture hex shroud;

FIG. 3 is a front view of the light fixture hex shroud;

FIG. 4 is a rear view of the light fixture hex shroud;

FIG. 5 is a top view of the light fixture hex shroud;

FIG. 6 is a bottom view of the light fixture hex shroud;

FIG. 7 is a left side view of the light fixture hex shroud (the right side view being a mirror image);

FIG. 8 is a cross-sectional view of the light fixture hex shroud taken along line 8-8 of FIG. 5;

FIG. 9 is an environmental view showing the light fixture hex shroud installed in a lighting can; and,

FIG. 10 is an environmental view showing the light fixture hex shroud installed in a lighting can.

The broken lines form no part of the claimed ornamental design.
